CAP

Dorothy Dear Hutton, New York, N. Y.

Application December 20, 1951, Serial No. 262,525

3 Claims. (Cl. 2-68)

1

This invention relates to caps for women and is directed to the provision of a bathing cap of a distinctive and improved form eliminating a deficiency of women's bathing caps as heretofore made. With those prior forms of caps, the operations of applying and removing the cap are accompanied by a derangement of the hair which is decidedly objectionable, so much so that it is of frequent occurrence that women do not go into the water when they would like to because this derangement causes an amount of inconvenience and annoyance for which the desired bath is insufficient recompense.

A common form of bathing cap for women as heretofore made is one which includes a close-fitting cap-part which comes down snugly over the head, so snugly that it may appropriately be termed a "skull" cap. This may be formed of an elastic material or be provided with elastic material at its edge and this elastic material is stretched in the operations of putting on the cap and removing the cap, and, when the cap is in place, the contraction of the elastic causes the edge of the cap to press upon the surface of the head enough to exclude water. Such a cap is satisfactory insofar as concerns the exclusion of water, but the operations of applying it and removing it, and the pressure applied to the hair while it is being worn, any one or all of these, result in deranging the hair to a disagreeable and regrettable extent.

Another type of women's cap available on the market and described in the literature is one which is not of the "skull" cap variety, but instead extends loosely over the head and is of a soft flexible material and is provided with an elastic extending part or all the way around the opening. Such a cap may be applied or removed only by stretching this elastic which is depended upon to hold the edge of the cap close to the face and neck to exclude water. In applying or removing a cap of this type, derangement of the hair occurs almost invariably to a greater or less extent, the extent of the derangement depending upon the care with which this elastic is stretched and held extended over a considerable part of its length throughout the operation of applying or removing the cap.

My improved cap is distinctive in that the cap or hood portion is of a soft pliable material and is of ample size to be applied and removed without mussing the hair. This hood or cap portion is applied or removed without any stretching of any part of its structure and means are provided whereby, when the operation of applying the hood

2

portion to the head has been completed without deranging the hair to any appreciable extent, then something else is done to effect the necessary tightening around the face to accomplish the exclusion of water.

Preferably the cap is made of a thin, stretchable material such as latex, and, as stated, the hood portion of the cap is of ample size to permit of putting it on and taking it off while in a limp, non-stretched condition without deranging the hair. Integral with this hood portion at the lower part of the sides thereof are lateral extensions in the form of strip members, which, when the cap has been applied to the head, project forwardly below the ears. These strip members may be grasped at their end portions and brought forward over the ears and upward over the forehead, stretching the material adequately in doing so, and then fastened over the forehead in any suitable manner, as for instance, by one or more snap fasteners. The stretching of the material of the strip members to accomplish this brings the strip members down closely upon the sides of the face and forehead of the wearer with the edge portions of the strip members overlying the front side edge of the hood portion of the cap, and, when the end portions of the strip members are snapped into securing position, the cap is sufficiently tight to exclude water. Incident to removing the cap, the strip members are unsnapped and released, whereupon they contract to their initial dimensions, and the cap is again a limp, flexible covering which may be removed from the head without deranging the hair in an operation which requires no particular care.

I have illustrated an embodiment of my invention in the accompanying drawings in which Fig. 1 is a front view of the cap, Fig. 2 is a side view in section, and Figs. 3 and 4 show the cap applied to the head of a wearer, Fig. 3 showing the cap before the strip members are stretched to their final position, and Fig. 4 showing the strip members stretched and fastened in their securing position.

The bathing cap as illustrated is made of a thin, light, limp, flexible material and is of such size that the hood portion 5 fits loosely over the head, so loosely that it does not derange the hair. After it is applied, it is drawn up to an adequately water-tight condition by strip members 6 and 7 of stretchable material extending forwardly from the portion 8 of the cap corresponding to the back of the head just below the level of the ears. Preferably the entire cap, the hood portion 5 and these integral tightening strip members 6 and 7,

are made of a thin, limp, stretchable material, such as latex.

The application of the cap to the head requires no stretching of this material and no application of force, and its application, even when accomplished without the exercise of any particular care, does not occasion derangement of the hair. Then when the hood portion has been applied, the integral stretchable strip members are drawn forwardly and upwardly along the face in front of the ears and up over the forehead. During such operation the lower edge portion 10 at the back of the cap will be caused to lie snugly against the back of the head at the base thereof and the strip members will be stretched to such an extent that their elasticity will cause them to lie closely against the sides of the face and against the forehead, with the rear edge portions 11 of the strip members overlying the front side edges 6 of the hood portion.

5. The end portions of the strip members are crossed at the middle of the forehead and fastened there in any suitable manner, as for instance by one or more snap fasteners 9, as shown in the drawing.

With these strip members so applied and fastened, they hold the edge of the hood portion at the back closely to the base of the head and at the sides and front closely to the sides of the face and to the forehead with the result that water is effectually excluded.

When it is desired to remove the cap, the strip members are released one from the other at the snap fastener and they contract to their original condition, whereupon the hood portion of the cap is released, and, on account of its large size and the limp condition of the material from which it is made, it may be removed from the head without the application of force to stretch any part of it and without deranging the hair.

In the foregoing, the cap is described as for use in bathing in which the wearer is at times submerged, but its uses extend beyond that. It is well adapted for use in taking a shower bath, and is useful also in a household or a hospital to exclude dust and odors from the hair, though for this latter use it may be found desirable to use a material other than sheet rubber for the head portion of the cap.

This improved form of cap may be applied and removed with great ease because there is no stretching to be performed incident to either of those operations, and because of that it may be applied and removed without deranging the hair. Once it has been applied, it may be tightened to exclude water, dust and odors in a simple operation conveniently performed of stretching the material of the side strip members to draw the back part of the hood portion in and seal the front portion over the face.

I claim:

1. A cap having a hood portion of limp, flexible material and of such larger size than the head of a person that it may be applied to the head without stretching and derangement of the hair, and also of such size that when placed

on the head the lower edge portion at the back will lie against the back of the head at the base thereof and the front side edges will lie forward of the ears, and strip members of elastic material extending forwardly from the lower portion of the front side edges of the cap, said strip members being so positioned with respect to the side edges of the hood portion at the front thereof that they may be stretched and drawn forwardly and upwardly over the sides of the face and the forehead, and over the said edges of the hood portion and fastened together in such position, thereby drawing the lower rear part of the hood portion against the base of the head at the back, the said edges of the hood portion being smooth on the inside to lie smoothly against the forehead and sides of the face when the strip members are stretched and held in place over them, to thereby more effectively effect a seal at the edges of the cap.

2. A cap having a hood portion of limp, flexible material and of such larger size than the head of a person that it may be applied to the head without stretching and derangement of the hair, and also of such size that when placed on the head the lower edge portion at the back will lie against the back of the head at the base thereof and the front side edges will lie forward of the ears, strip members of elastic material extending forwardly from the lower portion of the front side edges of the hood portion to overlie the front edges of the hood portion at the sides and top of the face, and cooperative fastener elements adjacent the ends of the strip members and adjacent the front edge of the hood portion at a position to lie above the top of the face, the distance between the fastener elements at the free ends of the strip members and their cooperative fastener elements at the front edge of the hood portion, when the cap is on a person's head, being such that the strip members must be stretched to cause engagement of the cooperative fastener elements, the said edges of the hood portion being smooth on the inside to lie smoothly against the forehead and sides of the face when the strip members are stretched and held in position over them by the cooperative fastener elements, and thereby more effectively effect a seal at the edges of the cap.

3. A bathing cap as defined in claim 2 in which the cooperative fastener elements on the hood portion are spaced lengthwise of the front edge thereof, whereby, in securing the strip members in place, their free end portions may be caused to overlap.

DOROTHY DEAR HUTTON.
